RAIL LUBRICATOR

Warren C. Heidenthal, Middletown, N. Y., assignor to American Brake Shoe Company, New York, N. Y., a corporation of Delaware

Application March 17, 1944, Serial No. 526,894

10 Claims. (Cl. 184—3)

1

The invention relates in general to railroad track equipment and more particularly to devices for lubricating the flanges of car wheels and the flange-engaging surfaces of the rails. The invention relates further to cable controlled operating mechanism which, when actuated by the passage of rolling stock, operates pumping apparatus for supplying lubricant to the rails.

The invention further relates to operating mechanism so constructed and arranged as to have substantially constant effective movement when operated by railway car wheels regardless of the condition of wear of the wheels. The invention further relates to devices for minimizing any change in relationship between operating mechanism mounted on the track and operating mechanism mounted on or within a lubricant reservoir spaced some distance from the track, caused by any slight shifting in the track due to movement of trains or other causes.

According to a preferred embodiment of the invention, the track operating mechanism includes a plunger arrangement having a ramp surface engageable by the treads of car wheels. A suitable housing is provided in which said plunger slides vertically. The plunger operates a bell crank arrangement to which the operating cable is connected. The bell crank has a cam surface so shaped that the bell crank moves a constant distance regardless of the distance through which the plunger is depressed by a small or large false flange on the wheel. If desired, the casing which supports the plunger may have a removable cover for inserting or removing shims between the plunger and a shoulder on the casing for controlling the uppermost position of the plunger and thus the effective operating movement of the bell-crank. The casing also may have a suitable recess for extra shims.

According to a preferred form of the invention, the lubricant reservoir may be located alongside the track at some distance therefrom so as to be substantially independent of wave movement of the track. The reservoir contains suitable pumps for pumping lubricant to the applying devices associated with the running rail for applying lubricant to the wheel flanges. At the top of the reservoir a suitable guideway is provided in which slides a shelf. The shelf pivotally supports a bracket which in turn supports at its rear a spring assembly. The bracket journals at its front end an operating drum around which is wound the operating cable. This cable has one end anchored in the spring assembly and the other end extends to the bell crank

2

of the track operating mechanism. A suitable driving clutch and a suitable check clutch are associated with the drum for converting the oscillatory or reciprocating movement of the cable into uni-directional motion for driving the lubricant pumps through a suitable chain and sprocket arrangement. The shaft which supports the drum and overrunning clutches also supports a yoke having a tubular portion. A protecting pipe extending to the track operating mechanism connects this tubular portion through a semi-rigid coupling and a similar tubular portion on the plunger casing by a similar coupling.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a plan view of the section of track to which a lubricating device according to the invention is applied;

Fig. 2 is a transverse vertical section taken on the line 2—2 of Fig. 1;

Fig. 3 is a vertical section through the top of the reservoir;

Fig. 4 is a plan section taken on the line 4—4 of Fig. 3;

Fig. 5 is a vertical section on the line 5—5 of Fig. 4;

Figs. 6 and 7 are sections taken on the lines 6—6 and 7—7 of Fig. 4 illustrating the overrunning clutches;

Fig. 8 is a vertical side view of the plunger mechanism taken on the line 8—8 of Fig. 2; and

Fig. 9 is a vertical section taken on the line 9—9 of Fig. 8.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects with-

out departure from the broad aspect of the invention.

Referring now to the drawings and more particularly to Figs. 1 and 2 for general description, the running rail to which the lubricator is applied is denoted by 15, resting on the usual ties 16 with the usual tie plates 17 interposed. Secured to the inner side of the rail 15 are the delivery plates 18 for delivering lubricant to the wheel flanges 36. The reservoir 19 comprises a tank set into the ground alongside the track so as to occupy a substantially fixed position unaffected by the movement of the rails or ties due to the passage of railway trains. The reservoir 19 houses a series of gear pumps 20 which deliver lubricant through pipes 21 to the delivery plates 18.

Secured to the running rail is a plunger assembly, including plunger 22 which operates a bell crank lever 23 to which is secured cable 24. The cable 24 extends through the wall of the tank 19 and is wrapped several times around the drum of an unidirectional clutch assembly 25 and is connected to spring assembly 26. Both spring assembly and clutch assembly are mounted upon a pivoted and slideable bracket 29. A chain 27 connects the clutch assembly and the pumps 20, it being understood that up and down movement of plunger 22 reciprocates cable 24, driving unidirectional clutch 25, in turn unidirectionally driving the chain 27 and the pumps 20. The cable 24 runs through a protective pipe 28 connected to the plunger assembly and to the bracket 29 to maintain the proper relationship between these parts in a manner described more fully hereinafter.

Referring now also to Fig. 9 the lubricant applying apparatus will now be described. The head 30 of T-rail 15 is cut away, as indicated at 31, and the delivery plates 18 are spaced from the rail by suitable gaskets or washers indicated by 32 to form a series of lubricant chambers 33 with the web 34, extending along the track. The delivery plates 18 are clamped to the running rail 15 by a series of nut and bolt assemblies indicated by 38. The several lubricant chambers 33 are supplied by branch pipes 35 supplied by the delivery pipes 21 and grease is fed to the wheel flanges 36 through delivery slots 39.

Attention is called to Heidenthal Patent No. 2,185,810, granted January 2, 1940, for a more complete description of the lubricant applying apparatus.

Referring now also to Fig. 8, the plunger assembly will now be described. Secured to the running rail 15 is a filler plate 41 which may extend the entire length of the applying device to reinforce the cutaway running rail, as disclosed in the above-mentioned Heidenthal Patent No. 2,185,810. The plunger assembly comprises a housing 42 made up of plate members suitably welded together. These members comprise side walls 43, bottom wall 44, top wall 46, side flanges 48, front wall 60 and shelf 54. The housing 42 rests on the base 45 of the rail 15 and is suitably bolted to the rail by nut and bolt assemblies 49. An inner plate 53 is interposed between the welded housing and the filler plate 41 and the bolts 49 pass through this plate to complete the housing 42.

Strengthening webs 50 connect the side walls 43 and side flanges 48. A shim cover 55 having a hold-down flange 56 and a depending abutment 57 gives access to adjustable shims 75 and houses spare shims 59 in a manner explained

hereinafter more in detail. A hold-down screw 58 passes through flange 56 into shelf 54 for removably holding the shim cover 55 in position. A tube 61 is welded to the lower end of front wall 60 to support the protecting pipe 28, as described more in detail hereinafter.

The plunger 22 comprises a head 69 having cam or ramp surfaces 70 and 71 to accommodate trains passing in either direction. The head 69 passes through an opening 47 in top wall 46. The plunger is provided with guide flanges 65 fitting in vertical grooves 64 in the side walls 43. The plunger has a shoulder 74 between which and top wall 46 the shims 75 are positioned.

The plunger 22 has a spring recess 66 containing a helical spring 67 centered upon a boss 68 on bottom wall 44. The plunger has a pair of ears 76 through which a pin 77 is passed. A roller 78 is journaled on pin 77.

A car wheel, having a flange 36 and a tread 37, is indicated diagrammatically in Fig. 9, to illustrate the position of the flange with respect to the delivery slots 39 and the position of the tread 37 with respect to the plunger 22.

The plunger 22 reciprocates vertically, being forced down by the passage of wheels on the running rail 15 and being urged upwardly by the return spring 67. This reciprocating movement operates, under pull of cable 24, a bell crank lever 23 journaled on a bolt 81 passing through the side walls 43 and acting as a shaft for the bell crank lever. The lever has a depending arm 82 having a concentric groove 83 on which rides the cable 24, the cable being suitably anchored in a recess 84. The circular shape of curve 82 provides an effective operating arm of constant radius throughout the reciprocating movement of the bell crank lever 23.

The bell crank lever 23 has an upper arm 85 having cam surfaces 86 and 87 cooperating with the roller 78. The cam surface 87 is so shaped that downward movement of the plunger 22 from the position shown, i. e. while roller 78 is riding on surface 87, causes the bell crank, under pull of cable 24, to move clockwise in Fig. 9. The cam surface 85 is so shaped that further downward movement of the plunger 22, i. e. while roller 78 is riding on surface 86 causes no further movement of the bell crank 23. The cam surface 87 thus constitutes a "fall" which permits movement of the bell crank 23 and the surface 86 constitutes a "dwell" which permits no movement of bell crank 23. The dot and dash lines in Fig. 9 represent the position of the arm 85 when the plunger is depressed sufficiently to cause roller 78 to ride on dwell 86.

It will thus be seen that the peculiar relationship between the plunger 22 and bell crank 23 results in a constant movement of the bell crank regardless of the amount of downward movement of the plunger 22 so long as the first stage downward movement of the plunger 22 carries it at least to a position where the roller 78 begins to operate upon the dwell 86. The wheel indicated in Fig. 9 represents a new wheel and its tread 37 is sufficient to move the plunger 22 downwardly at least through this minimum operating distance. As the wheel wears and a false flange forms at 37a upon the tread 37, the plunger 22 will be pushed downwardly to a greater extent depending upon the size of the false flange. But such additional operating movement of the plunger 22 will not result in any corresponding additional operating movement of

bell crank 23. During the "return" or upward movement of the plunger 22, movement of roller 78 on "dwell" 86 produces no movement of bell crank 23 but movement of roller 78 on "fall" 87 produces counterclockwise movement of bell crank 23 in Fig. 9.

Referring now also to Figs. 3 to 7, the reservoir 19 comprises a tank having a casing 88 set in the ground alongside the track so as to be independent of all movement of the track. The casing 88 has a removable cover 89 and houses a series of gear pumps 20 located in the bottom of the casing 88. These gear pumps are positioned with their drive shafts in line, with their inlet ports communicating with the lubricant in the casing 88 and with their discharge ports communicating with vertical pipes 90 connecting with the delivery pipes 21 through flexible hose couplings 91. There is a separate pump 20 for each of the four delivery pipes 21. The drive shaft of the end pump 20 has a sprocket driven by a chain 27 as described more in detail hereinafter. For a more detailed disclosure of the pumps, but not the drive therefore, attention is called to the above mentioned Heidenthal patent.

The pumps 20 are driven by the plunger 22 through a special shelf mechanism including overrun clutch 25 mounted in the top of the tank 20. This mechanism comprises spaced guides 92 extending across the tank from front to rear and secured to the walls by bolts 93. Slidable in these guides is a slide shelf or plate 94. Mounted upon slide plate 94 is the swivel bracket 29 having a base 95 and a projecting tongue member 96 adapted to slide under a hold-down lug 97 mounted upon the slide plate 94. A swivel bolt 98 passes through base 95 and slide plate 94. The swivel bolt 98 and hold-down lug 97 are arranged to permit a lateral swivelling movement of bracket 29 about pivot 99 as a center, this action being explained more in detail hereinafter.

The bracket 29 further comprises a post 99 supporting the spring assembly 26. Assembly 26 comprises a sleeve 100 secured to post 99 in which slides a plug or plunger member 101 having a recess 102 in which is anchored the end of cable 24. A helical spring 103 is centered on plug 101 and operates against a shoulder 104 on sleeve 100 having an opening through which cable 24 passes. It will be understood that the spring 103 normally helps hold the cable 24 in tension.

The bracket 29 supports a swivel head construction comprising spaced bearings 107 rising from plate 95 and through which a shaft 108 passes. Shaft 108 supports overrunning drive clutch 25 and overrunning check clutch 110, a yoke 111 having arms 112, and a sprocket 113. The pump drive chain 27 rides on sprocket 113.

The drive clutch 25 and the check clutch 110 may be of any desirable type of overrunning clutch and may be similar in construction. The drive clutch 25 comprises an outer ring 109 having a grooved periphery around which several convolutions of cable 24 are disposed. Within ring 109 is a hexagonal core 114 keyed to shaft 108. A plurality of rollers 115 are disposed between core 114 and ring 109 and springs 116 are secured to core 114 for the purpose of urging the rollers 115 into wedging contact with their respective surfaces.

The check clutch 110 comprises an outer ring 119 forming a casing and having a removable cover plate 120 within which is disposed a hexagonal core 122 keyed to shaft 108 and having rolls and springs corresponding to the rolls 115

and springs 116 of clutch 25. The outer ring 119 has spaced lugs between which is disposed a set screw 124 threaded into the adjacent bearing 107 to hold the overrunning clutch casing stationary.

It will be understood that the drive clutch 25 and check clutch 110 operate similarly but oppositely. For example, when the cable 24 rotates the drive clutch 25 in the direction of arrow A in Fig. 6, the clutch drives the shaft 108. Upon the return stroke of cable 24, the ring 109 overruns core 114. When shaft 108 is rotating in the direction of arrow A, check clutch 110 is overrunning, while when drive clutch 25 is overrunning, the check clutch 110 keeps shaft 108 from retrograde rotation.

The angular and linear positions of the bracket 29 are determined by movement of the running rail 15 acting through the protecting pipe 28. The yoke 111 has a tubular extension 123 connected to pipe 28 through a semi-rigid coupling 124 which may comprise a short length of relatively stiff rubberized hose. The other end of pipe 28 is connected to pipe 64 on plunger housing 42 by a similar semi-rigid coupling 126. The coupling 126 is clamped to its respective pipes 28 and 64 by band clamps 127. Similar band clamps are used for clamping coupling 124 to its pipe members 123 and 28 but are omitted for sake of clearness.

The protecting pipe 28 passes through an enlarged opening 125 in the wall of casing 88 which is sealed by a leather boot 128. Boot 128 has a restricted end 129 suitably bound to the pipe 28 and an enlarged end 130 suitably bound to a collar 131 secured to the tank around the opening 125.

In some cases it may be desirable to lengthen the ramp or cam surface 70 and 71 by providing laterally extending flanges (not shown) extending lengthwise of the running rail on the head 69 forming in effect a mushroom type head for the plunger. Also if desired, the adjusting shims 75 may be omitted and adjustment of the plunger movement may be obtained by inserting shims 45 between the bottom wall 44 of the plunger housing and the base 45 of the running rail 15 thereby raising or lowering the entire housing.

Operation and advantages

It will be understood that, normally with the plunger 22 in upper position, the reservoir spring 103 is compressed while the plunger spring 67 is expanded. However, the relative forces exerted by the springs is such that plunger spring 67 predominates, holding reservoir spring 103 in compression by cable 24. As the wheel tread 37 engages plunger head 69, the engagement is eased by the cammed surfaces 70 and 71 which also ease the release of the plunger as the wheel disengages the plunger. As the wheel depresses plunger 22, compressing spring 67, the bell crank lever 23 moves in such way as to permit the flexible cable 24 to be taken up by expansion of the reservoir spring 103. This movement rotates the outer ring 109 of the drive clutch 25 in such direction as to cause the clutch to retract or overrun and to impart no movement to the gear pumps 20. As the wheel tread 37 leaves the plunger head, the plunger spring 67 moves the plunger upwardly, which pulls the cable 24 out of the reservoir against the force of spring 103, imparting rotation to the ring 109 of drive clutch 25 in such direction as to drive the gear pumps 20.

It will be understood that, if desired, the action of unidirectional drive clutch 25 and check clutch

110 may be reversed so as to permit pumping action upon downward movement of the plunger 22 with correspondingly no pumping when the plunger moves upwardly, but it is preferred in most cases to provide pumping action only with upward movement of the plunger.

The cable 24 may be of any flexible material, such as steel or bronze, and is wrapped around the drum of clutch 25 several times with sufficient tension to prevent slipping, both when the clutch 25 is engaged for driving the pumps and when the clutch is free-wheeling. The two springs 67 and 103 maintain tension on the cable 24 at all times.

The peculiar relationship between the plunger and the fall and dwell surfaces on the bell crank provides a constant throw or amplitude of movement of the bell crank, regardless of the displacement of the plunger caused by the varying sizes of false flanges. Thus the cable movement is the same with a new wheel having no false flange as with a badly worn wheel with a large false flange. This assists in maintaining uniformity of lubricant feed. At the same time the rate of lubricant feed may be adjusted by changing the shims 75 between the plunger shoulder and the top wall. The shims 76 determine the upper position of the plunger roller 78 on the actuating cam surface 87. For any given wheel, the fewer the shims, the greater the plunger movement, and vice versa.

The adjustable shelf construction assists in maintaining the cable adjustment constant, regardless of vertical movement of the track, or horizontal movement of the track, either in the direction of the track or sidewise of the track. The pivotal connection between the yoke 111 and the shaft 108 permits the vertical movement of the track; the swivel bolt 98 permits longitudinal movement of the track; and the sliding plate 94 permits lateral movement of the track, all without disturbing the relationship between plunger spring 67, reservoir spring 103, and cable 24. The slight corresponding movement of upper drive shaft 108 with respect to the fixedly positioned pump shafts of the pumps 20 is taken care of by the length of drive chain 27. The semi-rigid couplings 124 and 126 are sufficiently rigid to maintain proper relationship between the parts and protect the reservoir equipment from vibrations caused by moving trains. The coupling 126 at the plunger mechanism also allows the slight angular or universal movement of the protecting pipe 28 with respect to the track caused by longitudinal or vertical movement of the track.

The reciprocating operating parts driven by the car wheels are light in weight, thereby reducing inertia, and have no wearable joints to introduce lost motion. Any wear in parts located between the main springs 67 and 103 is immediately taken up by these springs. The unidirectional clutches are especially efficient, substantially instantly transmitting force. Lost motion in the chain and sprockets may be kept very small and, in any event, the effect of any lost motion in these parts is minimized since these parts have no reciprocating motion but move unidirectionally.

While certain novel features of the invention have been disclosed and are pointed out in the annexed claims, it will be understood that various omissions, substitutions and changes may be made by those skilled in the art without departing from the spirit of the invention.

What is claimed is:

1. In a rail lubricator, a plunger mechanism comprising a filler plate adapted to fit the web of a running rail, a housing comprising side walls, a bottom wall and a top wall connecting said side walls and forming a housing recess, side flanges connected to said side walls and adapted to be bolted to the running rail, an inner wall secured to said side flanges, said side walls having vertical guideways, a plunger member having portions riding on said guideways and having a wheel contacting head, said plunger having a recess in its underside, a helical spring in said recess resting on said bottom wall for urging said plunger upwardly, said plunger having a shoulder, shims between said shoulder and said top wall, a shelf connecting said side walls and providing an opening for access to said shims, a cover for said opening, a roller journaled on said plunger, a bell crank lever journaled between said side walls and having a depending arm with a concentric wire-receiving way adapted to support an operating wire extending to a lubricant supply, said bell crank having an upper arm having a cam surface engaging said roller, said cam surface having an upper fall so shaped as to cause said bell crank to rock with first stage downward movement of said plunger and a lower dwell so shaped to impart no additional movement to said bell crank with further downward movement of said plunger.

2. In a rail lubricator, a plunger mechanism comprising a filler plate adapted to fit the web of a running rail, a housing comprising side walls, a bottom wall and a top wall connecting said side walls and forming a housing recess, side flanges connected to the inner ends of said side walls and adapted to be bolted to the running rail, an inner wall adjacent said filler plate and secured to said side flanges, said side walls having recessed vertical guideways, a plunger member having flanges riding in said guideways and having a beveled wheel-contacting head, said plunger having a recess in its underside, a helical spring in said recess centered on said bottom wall for urging said plunger upwardly, said plunger having a shoulder, shims between said shoulder and said top wall, a shelf connecting said side walls, a cover having a top wall with a depending inner wall forming an internal recess and resting on said shelf, said recess being adapted to hold spare shims, a roller journaled on said plunger, a bell crank lever journaled between said side walls and having a depending arm with a concentric wire-receiving groove adapted to support an operating wire extending to a lubricant supply, said bell crank having an upper arm having a cam surface engaging said roller, said cam surface having an upper fall so shaped as to cause said bell crank to rock with first stage downward movement of said plunger and a lower dwell so shaped to impart no additional movement to said bell crank with further downward movement of said plunger.

3. In a rail lubricator, a track having a lubricant-applying device, an operating member, a support for said operating member secured to said track, a lubricant reservoir spaced from the track and independent of movement thereof, said reservoir comprising a tank, pumping mechanism, a guideway, a shelf slidable in said guideway, a bracket mounted on said shelf, pivot means connecting said bracket and said shelf, a spring assembly supported by said bracket, a drive assembly supported by said bracket, said drive assem-

bly including supporting bearings on said bracket, a shaft journaled in said bearings, a drive device on said shaft and connected to said pumping mechanism, a drum journaled on said shaft, an overrunning clutch operating between said drum and shaft, a check clutch having a casing fixed to an adjacent stationary part and a movable member secured to said shaft; a protecting pipe having pivot connection with said shaft and having a universal connection with said operating member support; a cable connected to said operating mechanism passing through said pipe, wrapped around said drum and connected to said spring assembly, and conduit means connecting said pumping mechanism and applying device.

4. In a rail lubricator, a track having a lubricant-applying device, an operating member, a support for said operating member secured to said track, a lubricant reservoir spaced from the track and independent of movement thereof, said reservoir comprising a tank, pumping mechanism, a guideway extending across said tank, a shelf 10 slideable in said guideway, a bracket mounted on said shelf, pivot means connecting said bracket and said shelf, a spring assembly supported by said bracket, a drive assembly supported by said bracket, said drive assembly including supporting bearings on said bracket, a shaft journaled in said bearings, a sprocket on said shaft, a chain connecting said sprocket and said pumping mechanism, a drum journaled on said shaft, an overrunning drive clutch operating between said drum and shaft, a check clutch having a casing fixed to an adjacent bearing and a movable member secured to said shaft, a yoke engaging said shaft; a protecting pipe connected to said yoke and having a semirigid connection with said operating member support; a cable connected to said operating member, passing through said pipe, wrapped around said drum and connected to said spring assembly, and conduit means connecting said pumping mechanism and applying device.

5. In a rail lubricator, a running rail having a lubricant-applying device, an operating member, an operating support for said operating member secured to said running rail, a lubricant reservoir anchored in the ground alongside the track and independent of movement thereof, said reservoir comprising a tank, pumping mechanism in the bottom of said tank, spaced guides extending across the top of said tank, a plate having parts slideable in said guides, a bracket mounted on said plate, pivot means connecting said bracket and plate at the forward end thereof, a hold down flange on said plate at the rear end thereof, a lug on said bracket under said flange, a spring assembly supported at the rear side of said bracket, a drive assembly at the forward side of said bracket, said drive assembly including supporting bearings on said bracket, a shaft journaled in said bearings, a sprocket overhung on said shaft, a chain connecting said sprocket and said pumping mechanism, a drum journaled on said shaft between said bearings, an overrunning clutch within said drum and operating on said shaft, a check clutch on the outer side of one of said bearings having a casing fixed to the adjacent bearing and a movable member secured to said shaft, a yoke having bearings engaging said shaft and having a tube; a protecting pipe having a semi-rigid connection with said tube and a similar connection with said operating support, a cable connected to said oper-

ating member passing through said pipe, wrapped around said drum and connected to said spring assembly, and conduit means connecting said pumping mechanism and applying device

6. In a rail lubricator, a track having a lubricant-applying device, a reciprocable wheel-contacting operating member, a support for said operating member secured to said track, a lubricant tank spaced from said track and supported so as to be independent of movement thereof, pumping mechanism in said tank, conduit means between said pumping mechanism and said applying device, a transfer base, means movably mounting said base in said tank, a spacing device connected to said track and to said base, said spacing device being substantially non-yielding in a direction lengthwise of itself so as to cause said base to shift with shift of said track, a transfer drive device on said base, first drive mechanism extending between said operating member and said transfer drive device, and second drive mechanism between said transfer drive device and said pumping mechanism.

7. In a rail lubricator, a track including a running rail having a lubricant-applying device, a reciprocable wheel-contacting operating member, a support for said operating member secured to said running rail, a lubricant tank spaced from said track and supported so as to be independent of movement thereof, pumping mechanism in the bottom of said tank, conduit means between said pumping mechanism and said applying device, a transfer base, means movably mounting said base in the top of said tank, a protecting device connected to said running rail and to said base, said protecting device being substantially non-yielding in a direction lengthwise of itself so as to cause said base to shift with shift of said running rail, an overrunning drive device journaled on said base, a reciprocable drive mechanism protected by said protecting device and extending between said operating member and said overrunning drive device, and uni-directional driving mechanism extending between said overrunning drive device and said pumping mechanism.

8. In a track lubricator, a track having a lubricant-applying device, a lubricant tank, delivery apparatus for transferring lubricant from said tank to said applying device, a reciprocable plunger member mounted on said track to be engaged by wheels running on said track, a drive member operatively connected to said delivery apparatus, an operating mechanism between said operating member and said driven member for driving the latter, said operating mechanism including a cam element and a roller in engagement therewith, said cam element being movable with said driven element, said roller being journaled on said plunger member, said cam element having a fall portion and a dwell portion, said roller moving along said fall portion with the first part of movement of said plunger member caused by a car wheel, said roller moving along said dwell portion with further movement of said plunger member beyond said first part movement, whereby said operating mechanism transmits said first part movement of said plunger member to said driven member and does not transmit said further movement of said plunger member to said driven member.

9. In a track lubricator, a track having a lubricant-applying device, a lubricant tank, delivery apparatus for transferring lubricant from said tank to said applying device, a reciprocable op-

erating member mounted on said track to be engaged by wheels running on said track, a driven member operatively connected to said delivery apparatus, an operating mechanism between said operating member and said driven member for driving the latter, said operating mechanism including a cam element and a follower element, one of which is connected to move with said operating member and the other of which is connected to move with said driven member, said cam element having a fall portion and a dwell portion, said follower element moving along said fall portion with the first part of movement of said operating member caused by a car wheel, said follower element moving along said dwell portion with further movement of said operating member beyond said first part movement, whereby said operating mechanism transmits said first part movement of said operating member to said driven member and does not transmit said further movement of said operating member to said driven member.

10. In a track lubricator, a track having a lubricant-applying device, a lubricant tank, delivery apparatus including a pump for transferring lubricant from said tank to said applying device, a guide member on said track, a reciprocable plunger member mounted in said guide member in position to be moved downwardly by the false flanges of wheels running on said track, spring means held by said guide member to urge said plunger member upwardly, an overrunning clutch operatively connected to said pump, an operating mechanism acting between said plunger member and said overrunning clutch for driving the latter, said operating mechanism including a cam element and a follower element, one of which

is connected to move with said plunger member and the other of which is connected to move with said overrunning clutch, spring means retracting said overrunning clutch and holding said cam element and follower element in engagement, said cam element having a fall portion and a dwell portion, said follower element moving along said fall portion with the first stage of downward movement of said plunger member, said follower element moving along said dwell portion with the second stage of downward movement of said plunger member, whereby said operating mechanism transmits said first stage movement of said plunger to said overrunning clutch and does not transmit said second stage movement of said plunger to said overrunning clutch, said overrunning clutch having its driving action in such direction as to cause said pump to deliver lubricant with upward movement of said plunger.

20 WARREN C. HEIDENTHAL.
